ABSTRACT OF THE DISCLOSURE

A complete self-contained compound tool, useful in particular as a carburetor-distributor adjustment device. It incorporates a flexible shaft-flexible tube combination that is capable of functioning through a tortuous path and integrates in a single head two implements, a hex key and a screw driver, each being rendered alternately usable by a sliding head adjustment.

This invention relates to a versatile compound rotary hand tool with a flexible shaft and distinct work engaging elements whose respective elements may be alternately positioned for use to engage either of two different work pieces, e.g. two different kinds of screws, for example, slotted or hex screws; a screw and a nut; etc.

In many operations, access to locations where a tool must be used presents serious difficulties and in others where the tool can be inserted, the operation is very time consuming. The tool of the present invention is aimed at alleviating such difficulties. It will be described in conjunction with its use as a carburetor and electrical current distributor adjustment tool for multicylinder engines where it finds particular advantages, although its use is not restricted thereto because it will be apparent that the tool may be advantageously used in other applications.

It is an object of the present invention to provide a novel compound rotary hand tool characterized by a flexible shaft which permits its use in difficultly accessible locations and tolerates bending of the shaft in more than one plane and in arcs exceeding 360° without interfering with its use.

It is another object of the present invention to provide a novel rotary compound hand tool whose respective tools which may be used in the alternate are positioned in a single head in telescoping relationship.

It is another and more specific object of the invention to provide a novel carburetor and electrical distributor adjustment tool, i.e. a device to adjust contact breaker points which direct the electrical current from the coil to the various spark plugs and to adjust fuel-air mixtures characterized by a hex key for engaging an Allen screw and a screw driver arranged to telescopically extend and retract linearly over said hex key to permit the engagement of the screw driver with a cross cut screw head.

Other objects and advantages of the invention will be apparent from the detailed description, provided herein-after when considered in connection with the accompanying drawing wherein:

FIG. 1 is a perspective view, partly in section, of the tool of the present invention.

FIG. 2 is a fragmental view partly in section, illustrating the assembly in the handle of the flexible shaft and surrounding flexible tube.

FIG. 3 is a fragmental view, partly in section, of the head, or implement end of the tool, showing a portion of the flexible shaft and flexible tube with the sleeve part of the head retracted and the hex key tool centrally located in the sleeve is extended in operable position.

FIG. 4 is a fragmental view similar to FIG. 3 except that the sleeve on which the screw driver is mounted is

2

extended so that the screw driver is positioned beyond the end of the hex key.

FIG. 5 is a detailed sectional view taken substantially in a plane shown by line 5-5 of FIG. 3.

FIG. 6 is a detailed sectional view taken substantially in a plane shown by line 6-6 of FIG. 3.

In accordance with the present invention, the compound tool comprises a flexible rotatable shaft which is housed in a flexible tube and secured to a handle for turning at one end. The shaft is secured at the other end to a first work piece engaging tool element which is concentrically positioned within a sleeve carrying near its end a second tool element e.g. a screw driver; the latter may be extended linearly beyond the extremity of the first tool element to engage a work piece and alternately it may be retracted to permit instead the use of the now relatively extended first tool element.

Referring in greater detail to the various figures in the drawing wherein similar reference numerals refer to similar parts, the tool comprises a flexible shaft 11 securely attached at one end to a handle 13 by means of handle insert 12, and at the other end to a head assembly 17 by adapter 16. The shaft 11 is enclosed within a flexible tube 10 and allowed to freely rotate relative thereto. In use, the tube 10 and the adapter 16 attached thereto, remain relatively stationary as the shaft 11, handle 13 and the head 17 are rotated in unison. The flexible shaft 11 and flexible enclosing tube 10 are of conventional commercially available structure. The make up of shaft 11 is practically a solid structure which includes a single central wire or mandrel over which a plurality of successive layers of wire are wound concentrically, each successive layer alternating in pitch and direction. The shaft 11 is secured to the handle 13 by any suitable means such as by the handle insert 12 which comprises ferrule-like portion extending over the end of the flexible tube 10, and a reduced portion or stub 15. Handle stub 15 is press fitted into handle 13. Stub 15 may be advantageously provided with a fluted threaded or comprise other irregular surfaced segment 14 to improve the grip of the insert within the handle into which the stub 15 of the insert 12 may be forced. The segment 14 may be also secured by other suitable means such as adhesive. The handle 13 is preferably fluted to provide a better grip and may be formed of any suitable composition such as wood, rubber, or any of various plastics such as cellulose acetate butyrate, polystyrene, polycarbonate, polyethylene, polypropylene, and the like.

The handle end of the tube 10 is carried within, but allowed to rotate with respect to, the ferrule part of handle insert 12 and appropriately secured therein such as by crimping.

At the other end of the flexible shaft 11 from the handle 13, a head 17 comprising a slide 18 and a telescoping sleeve 22 is attached. The head may be securely engaged to the shaft 11 by suitable connection such as by crimping one end of the slide 18 over the end of the flexible shaft 11. The flexible shaft 11 is inserted into the flexible tube 10 after assembly of the slide 18 on the flexible shaft 11. The slide 18 at the other end carries a tool element such as the hex key 21.

The sleeve 22 in its forward part is provided with a screw driver element 25 which is secured in the sleeve 22 such as by a pressed fit. The screw driver element 25 has a central passage 27 through which the hex key 21 passes and tongue or screw driver portions 26 which fit in the slot of a conventional screw. Shown in phantom at 32 and 33 are an Allen screw and a conventional slotted screw engageable by hex key 21 and screw driver 26 respectively.

The slide 18 is provided with one integral formed groove 20 at one end, and a detent 19 of approximately $3\frac{1}{32}$ x

.025-.030 in depth. This groove 20 and detent or recess 19 (spot drilled) function as stops and their function is to receive a $\frac{3}{32}$ steel ball 24, which is used as a locking device, the steel ball 24 being held in this position by pressure exerted by an encapsulated spring 23, which is carried by the sleeve 22. The ball 24 extends through an appropriate aperture to permit constant contact with the slide 18. Locking pressures are determined by the forces of the spring 23. The forces required to disengage the sleeve 22 over the slide are directly proportional to the forces of the spring 23. In disengaging from the extended position of slide 22 (FIG. 4) (or screw driver end), the sleeve is movable longitudinally rearward towards spot 20 thereby exposing the hex end for inserting into any aperture requiring same. The sleeve 22 in this position is held by the $\frac{3}{32}$ " ball 24 and spring 23 in the spot detent 19. Hex key 21 can now be utilized.

Disengagement pressures can be regulated by varying the spring tension. This can be done in several ways: By increasing the spring thickness, thereby increasing tension; conversely by decreasing spring thickness and reducing tension. By increasing the depth of the groove 20 on the sleeve 22, i.e. increasing the penetration of the $\frac{3}{32}$ ball. By a combination of both items 1 and 2. In the event the spring 23 should break, weaken, or for any other reason become detached from the slide 18, thereby permitting the $\frac{3}{32}$ ball to escape, the slide 18 cannot be removed, lost or damaged, from the sleeve 22; detachment is prevented by the combination of inside diameter of the sleeve 22 and outside diameter of slide 18. By inserting a new ball and spring, the tool is now rendered workable.

The sleeve 22 may be provided with a knurled portion 29, or other friction surface, to facilitate gripping and movement of the sleeve 22 over the slide 18. As shown more clearly in FIGS. 3 and 4 the forward end of the tube 10 is provided with an annular adapter 16 (which is secured to tube 10 or by crimping) through which the shaft 11 passes and which contains the end of the tube 10. It is thus seen that in use all parts of the tool rotate except tube 10 and adapter 16.

The compound tool depicted and described in detail is particularly adapted for adjusting distributors and carburetors in automobiles. The shaft and tube are readily twisted to conform to the most convenient positioning within the permitted working space. The tube is so flexible that it may be twisted more than 360° in one plane and at the same time in an acute angle in another plane and still perform satisfactorily.

As shown in FIGS. 1 and 3, the tool is set in a position to permit use of the tool element 21. When the alternate tool, the screwdriver element 25, is to be used, the sleeve portion 22 is extended to the position shown in FIG. 4 by moving sleeve 22 linearly with sufficient force to lift the ball 24, against the force of spring 23, from spot 19 and reposition it in groove 20. The screwdriver 26 is now ready for use. The hex key 21 may be advantageously

inserted through the slide door in the side of distributor cap to adjust the contact breaker points while the screwdriver 26 as noted may be used to adjust carburetors.

Various modifications apparent to one skilled in the art may be made in the compound tool of the present invention without departing from the teaching provided herein. It is therefore to be understood that the invention may be practiced within such modifications and still be within the scope of the appended claims.

I claim:

1. A compound tool comprising a rotatable flexible shaft, a handle secured at one end of said shaft, a compound tool head secured at the other end of said shaft, said shaft, handle and head being rotatable in unison, said head comprising a slide portion secured to said shaft at one end and a first tool element at the other end and a telescoping sleeve movable linearly in forward and rearward lockable positions with respect to said slide and tool element, said sleeve carrying a second tool element at its forward end adapted to function when said sleeve is placed in its forward position, and a flexible tube surrounding said shaft and attached to and extending from said handle to said head, said tube remaining relatively stationary to said shaft and handle when the handle is rotated.
2. The tool of claim 1 wherein said slide is provided with an annular groove near one end and a recessed spot near the other end and said slide is provided with a ball and a ball retaining lock spring and wherein said ball is adapted to be moveably engageable in said groove and spot.
3. The tool of claim 1 wherein said first tool element is a hex key and said second tool element is a screw driver.
4. The tool of claim 1 wherein said sleeve is provided with a friction enhanced portion on its outer surface.
5. The tool of claim 2 wherein said first tool element is a hex key and said second tool element is a screw driver.
6. The tool of claim 5 wherein said sleeve is provided with a knurled friction enhanced outer surface and said handle comprises a fluted construction.
